Charles C. F. Nieschang INVENTOR

BY
H. G. Burns ATTORNEY

UNITED STATES PATENT OFFICE.

CHARLES C. F. NIESCHANG, OF FORT WAYNE, INDIANA.

INDICATOR.

1,132,282.

Specification of Letters Patent.

Patented Mar. 16, 1915.

Application filed July 3, 1912. Serial No. 707,620.

To all whom it may concern:

Be it known that I, CHARLES C. F. NIESCHANG, a citizen of the United States of America, and resident of Fort Wayne, in the county of Allen and State of Indiana, have invented certain new and useful Improvements in Indicators, of which the following is a specification.

This invention relates to improvements in indicators of that class used in traffic between venders and their customers to indicate to the vender the quantity of merchandise desired by the customer, and the object thereof is to provide a device of its class which will be of conventional form and its operation easily understood by both the customer and the vender.

The object of the improvement is accomplished by the construction illustrated in the accompanying drawings in which:—

Figure 1 is an elevation showing the inner face of one of the plates of which the device is composed; Fig. 2 is a similar view of the other plate of which the device is composed; Fig. 3 is a front elevation of the device complete; and Fig. 4 is a similar view of the same but set in a different indicating position.

Similar numerals of reference indicate corresponding parts throughout the several views and referring now to the same: 1 is a rectangular plate composed of card-board, metal or other suitable material, and 2 is a similar plate corresponding in dimensions with the former plate. Each of the plates has near one of its corners an aperture, 3 and 4 respectively, and between the aperture and the adjacent corner is a small opening 5, which may be eyeleted, if desired, the opening being for the purpose of receiving a nail placed for the purpose of hanging the device in position. The plates 1 and 2 are placed face to face, one upon the other, and secured together at their centers by means of an eyelet 6, so that one plate may be turned upon the eyelet relative to the other.

Upon the inner face of the plate 1 is arranged a series of colored faces 7, each bearing an indicating numeral and located equidistant from the center 8 of the card. Also one of the corners of the plate has a colored face 9, the color being of the same hue as the other faces of the plate. The plate 2 also has upon its inner face a corresponding se-

ries of colored faces 10, each bearing a different indicating numeral, and similarly located to those on the former card. The card 2 has also a colored face 11, in the corner thereof opposite its aperture 4. The colored faces of the two cards are of different hue: For instance, those on the card 1 may be blue, while those on the card 2 may be red, or some color that will contrast sharply from the color used on the other card. When the two plates are secured together, the face of each having the colored faces is placed inward so that the series of faces 10 on the card 2 may be brought successively to the opening 3 of the card 1, and likewise the series of faces 7 on the card 1 may be brought successively to the opening 4 in the card 2. The series of faces 7 on the card 1 and the corresponding series on the card 2 are so located on the respective cards that they will appear at the aperture of the opposite card when one of the cards is turned to an angle of 45 degrees relative to the other card, as shown in Fig. 3, with the exception of the face on each card nearest the corner of the card, which has the colored face 9 or 11, as the case may be. These appear at the apertures when one card is placed square with the other and with their apertures oppositely disposed, as shown in Fig. 4. When the front 12 of the card 1 is displayed, the series of faces 10 of the card 2 may be made to appear through the aperture 3 of the former card, and as the card is turned to its various indicating positions at an angle to the card 1, the face 11 in the corner of the card 2 will appear beyond the edge of the card 1 upon one side thereof or the other accordingly as the card is turned. When the cards are made to register with one another, as shown in Fig. 4, the face 11 will not appear to view but will be obscured by the corresponding corner of the card 1. However, it should be noted that when adjusted to the position last described, the outline of the device shows a four-cornered figure, while when the cards are adjusted at an angle to one another, as previously described, an eight-pointed figure is displayed.

Either side of the device may be displayed, and by the use of the differently colored faces marked with numerals so as to have graded significance, and also by the adjustments of the cards so as to afford a rectangular or eight-pointed appearance as

the case may be, the meanings of the various 5 adjustments of the device becomes readily comprehensible. For instance, should the device be adjusted to one of its rectangular positions, it would readily be comprehended by one familiar with the device that one or the other of the two highest numbers on the colored faces would be displayed in signal 10 position, and the color appearing in the aperture would signify which of the two highest numbers shows; and when the device is adjusted to one of its eight-pointed positions, the color displayed signifies which of the colored series of faces, those of lower or higher denomination, appears, while the position of the colored face in the corner of the 15 card indicates which one of the colored faces of that particular series appears at the aperture. Thus, while the numbers appearing 20 upon the colored faces may not readily be read at a distance, the signal displayed by the device may be quickly and accurately ascertained when viewed, even from a point

considerably distant from the point where displayed.

Having described my invention what I claim as new and desire to secure by Letters Patent is:—

A device of the class described, comprising two rectangular plates of similar dimensions pivotally secured together, each plate having an aperture between its pivotal point and one of its corners, and having an annular series of indicating faces concentric with its pivotal point, any one of which may be made to appear through the aperture of the other plate, and also another indicating face that may be made to appear beyond the edge of the other plate.

In testimony whereof I affix my signature, 40 in presence of two witnesses.

CHARLES C. F. NIESCHANG.
